UNITED STATES PATENT OFFICE

ARTHUR GOMMESSEN, OF GRAND RAPIDS, MICHIGAN, ASSIGNOR TO THE KIEL FURNITURE COMPANY, OF MILWAUKEE, WISCONSIN, A CORPORATION OF WISCONSIN

RADIOTABLE

Application filed June 24, 1929. Serial No. 373,211.

This invention relates to improvements in radio tables, more particularly arranged for containing a complete radio apparatus.

It is one of the objects of the present invention to provide a radio table in which a complete radio apparatus and a dynamic speaker may be so concealed that the table will have the appearance of being an ordinary occasional table, while permitting easy accessibility for operating the radio controls and station selectors.

A further object of the invention is to provide a radio table having a hinged side panel to permit access to the operating knobs, and a hinged top to permit access to the parts.

A further object of the invention is to provide a radio table having means for concealing the dynamic speaker within the upper portion of the table beneath the top, or in the lower stretcher portion of the table.

A further object of the invention is to provide a radio table having tubular legs with side outlets to conceal the wires extending to the electric light socket wires and the ground and antenna wires from the table.

A further object of the invention is to provide a radio table which is of simple construction, is strong and durable and is well adapted for all uses to which an occasional table may be used, and in addition may be used for containing a radio instrument and dynamic speaker.

With the above and other objects in view, the invention consists of the improved radio table and its parts and combinations as set forth in the claims, and all equivalents thereof.

In the accompanying drawings in which the same reference characters indicate the same parts in all of the views:

Fig. 1 is a perspective view of the improved radio table, the front panel being swung downward to permit access to the operating knobs;

Fig. 2 is a top view of the table with the greater portion of the table top removed to show interior construction;

Fig. 3 is a vertical longitudinal sectional view taken on line 3—3 of Fig. 2;

Fig. 4 is a vertical transverse sectional view taken on line 4—4 of Fig. 2;

Fig. 5 is a sectional detail view of one of the tubular legs taken on line 5—5 of Fig. 3; and

Fig. 6 is a perspective view of the lower portion of the table showing the dynamic speaker mounted in the stretcher portion of the table.

Referring to the drawings, the reference numeral 8 indicates a table top, 9 the body or compartment portion which is formed in part of side panels 10 positioned beneath the top, 11 the supporting legs, and 12 the stretcher or lower brace member which connects the lower portions of the legs together. The table may be of any shape desired, and in the form shown, the legs extend upwardly to the top and the side panels are interposed therebetween, and with the exception of the front panel 10' are rigidly connected to said legs. Bottom boards or members 13 and a downwardly offset bottom board or member 14 complete the formation of the body portion. The bottom members 13 are spaced apart to provide space 15 for a radio receiving instrument 16 and a loud speaker 17 of the dynamic type. Angle brackets 18 connected to the bottom members 13 depend downwardly therefrom, and at their lower end portions are connected to the bottom member 14 which is adapted to support the radio instrument 16. The loud speaker 17 is supported upon metal bracket straps 19 of angular formation which straddle the space 15 between the bottom boards 13 and depend downwardly therefrom to provide the proper space for the speaker 17 which is supported thereon.

The front panel or cover 10' is hinged to the front lower edge portion of the bottom board 14 and is arranged to swing downwardly to open horizontal position as shown. A spring latch button 20 holds the cover in closed position. The cover when in open position exposes for manipulation the dial and rheostat knobs 21 of the radio apparatus. A supporting arm 22 engaging the cover and the body of the table supports said cover when in open position.

The table top 8 is hinged at its rear edge 10a

portion to the body of the table to swing upwardly, as indicated by dotted lines in Fig. 4, to permit access to the interior portions of the radio apparatus. A two-part brace bar 23 holds the top in open position.

The two rear legs 11' are of tubular construction to conceal the wires extending up to the radio instrument, the antenna wire 24 extending through the left rear leg, and the ground wire 25 and the current supply wires 26 extend through the right-hand rear leg 11', as indicated in Fig. 2. The wires extending through the tubular legs terminate in connector receptacles or sockets 27 for connection with plugs having wires 28, 29 and 30 connected thereto, and thus provide for connection with sources of current supply and with antenna and ground.

In Fig. 6 the loud speaker 17 is mounted in the central opening 31 of the stretcher and a grille panel 32 covers the open end of the cone.

Particular attention is directed to the vertical position of the axis of the cone, which is of great advantage in carrying sound to all portions of the room in which the instrument is placed, and further, the vertical position of the cone eliminates the cone rubbing on one side of the center pole of the electromagnet used in dynamic speakers. Furthermore, the vertical position of the axis of the cone of the speaker serves to direct the volume of sound evenly throughout all portions of the room, and thus eliminates directional travel of the sound waves. The location of the dynamic speaker in the body of the table provides the necessary sounding board and compartment to produce the desired tone value for the operation of the dynamic speaker.

From the foregoing description, it will be seen that the radio table provides an ornamental table which may be used as a table, and in addition the radio instrument concealed therein may be easily operated.

What I claim as my invention is:

1. In combination with a radio table having a radio receiving apparatus concealed beneath the forward portion of the table top by side panels, of a radio loud speaker concealed beneath the rear portion of said top by said panels and disposed so as to deliver sound waves downwardly and outwardly beneath said panels.

2. In combination with a radio table having a radio receiving apparatus concealed beneath the table top by side panels, of a radio loud speaker likewise concealed beneath said top by said panels and disposed so as to deliver sound waves downwardly and outwardly beneath said panels, and wires leading to said receiving apparatus and extending through a leg of the table.

3. In combination with a radio table having radio receiving apparatus supported thereon, a table top having supporting legs

and side panels, a radio loud speaker concealed beneath said top by said panels and disposed so as to deliver sound waves downwardly and outwardly beneath said panels, and wires leading to the receiving apparatus and extending through a leg of said table.

4. In combination with a radio table having a radio receiving apparatus concealed beneath the forward portion of the table top by side panels, a radio loud speaker concealed beneath another portion of said top by said panels and disposed so as to deliver sound waves downwardly and outwardly beneath said panels.

5. In combination with a radio table having a radio receiving apparatus concealed beneath the forward portion of the table top by side panels, a radio loud speaker located laterally adjacent to said receiving apparatus and concealed beneath another portion of said top by said panels, said loud speaker being disposed so as to deliver sound waves downwardly and outwardly beneath said panels and between the legs of said table.

In testimony whereof I affix my signature.

ARTHUR GOMMESEN.
